UNITED STATES PATENT OFFICE.

CHARLES F. KIMBALL, OF CHICAGO, ILLINOIS.

SLEIGH.

SPECIFICATION forming part of Letters Patent No. 339,992, dated April 13, 1886.

Application filed February 12, 1886. Serial No. 191,730. (No model.)

To all whom it may concern:

Be it known that I, CHARLES F. KIMBALL, a citizen of the United States, residing at Chicago, in the county of Cook and State of Illinois, have invented certain new and useful Improvements in Sleighs, of which the following is a specification, reference being had thereto in the accompanying drawings.

Figure 1 is a side elevation of a sleigh constructed according to my invention. Fig. 2 is a front elevation of the front bent post of said sleigh. Fig. 3 is a detail in perspective from the front, showing the shaft-jack back of the front post. Fig. 4 is a perspective view of the curved iron on the front bar. Fig. 5 is a cross-section on line *x x* of Fig. 2. Fig. 6 is a side elevation in detail of the shaft-jack and front post, showing the jack slightly forward of the post.

This invention belongs, more particularly, to that class of sleighs known as "trotting-sleighs;" and the special feature of novelty consists in the construction of the curved front post, in the strengthening-iron, preventing the post from spreading, in the attachment of the shaft-jack, and in the construction and combination of the parts, all as will now be set out more fully. In this class of sleighs it is necessary that the horse should be harnessed very much nearer to the sleigh-body than is possible in sleighs of the ordinary construction. When it is attempted to bring the horse near the sleigh of ordinary construction, he is brought so near to the sleigh that there is the greatest danger of his hind feet or heels striking the front posts of the sleigh. This is apt to be harmful in two ways—namely, to the sleigh and to the horse; but if neither of such consequences follows, the sleigh is likely to touch occasionally on the horse's legs, which at once breaks the horse's gait and puts an end immediately to the trotting. By the present invention all the likelihood of such accidents and objections is avoided by using a long front bar, and in this way spreading the front posts apart at the top far beyond the ordinary width, and by attaching the shaft-jack back of the front post. Thus the horse can be brought very close to the sleigh without the least danger of harm to himself or of his harming the sleigh, and a very much needed class

of sleighs—namely, trotting-sleighs—is produced; but though this invention is generally designed to produce such a sleigh, it is equally well adapted for any ordinary use, giving the driver far better control of his horse than any ordinary sleigh possibly can.

In the accompanying drawings, *A* denotes the sleigh, and *a* the thill or shaft. At the front part of the sleigh is placed the long and arched bar *B*, the lower ends of which constitute the posts. On the inside of this bar and under its arched top, in part, are the metal strengthening-strips *C*, while on the face of the arched portion of said bar is the metal strip or piece *E*, all of said strips or pieces being secured on and to said bar in any usual way or manner. The strips *C* and *E* are made in the shape shown in Figs. 4 and 5, the portion at the bends *c* being very considerably thickened. The strip *E* is attached to the rear of the post and bar *B*, and runs the entire length of the top of the bar and a little way down the sides. As thus made, when they are applied to the post, they afford peculiar strength at the points where the greatest strain comes—viz., the bends—which is a feature of great value in this structure. The strips *C* extend from a point near the middle almost the whole length of the bar and post, and their ends are secured on each side to the runners *D* by bolts or pins *c'*, which pass through the ends of said strips and the runners. The ends of these strips may also be secured in and to the runners by mortise and tenon. In this construction the front bar and post become one. Its main upper part being extended quite across the front of the sleigh, a free and open space is secured at the fore part of the sleigh of nearly double that in ordinary sleighs. The shaft-jack *F* is placed at the junction of the rods *G* and *H*, which extend to the forward bent part of the runner and the curved iron rod *I*, which is fixed at its inner end to the bend of the post. By this construction the jack can be brought to position just to the rear of the post. This is considered the most desirable; but a slight change so as to bring the jack abreast of the post or very slightly forward of it would not materially change its function, because even in this way the horse would still be attached

close to the sleigh. By this construction and arrangement of the post and shaft-jack the horse can, when harnessed, stand close to the sleigh, and when in action will have opportunity for the free movement of his hind legs without any danger of hitting any part of the sleigh. It will also be noticed that one important advantage in placing the shaft-jack as described is, that the shafts can be turned up straight, as shown in dotted lines in Fig. 1. In this way the sleigh will take up but little room in the stable.

I am aware that heretofore in sleighs the knees have been strengthened by angle-irons, and that these have sometimes been stiffened by an inwardly-projecting web. I do not claim such devices or construction, because neither the one nor the other will at all answer the purposes of the present invention.

This sleigh can be made very lightly and ornamental, and will not in appearance differ much, to the casual observer, from any ordinary sleigh, as all the other parts of the sleigh can be made and brought together in any well-known manner.

Having now described my invention, what I consider new, and desire to secure by Letters Patent, is—

1. A trotting-sleigh having a long front arched bar, constructed as described, combined with a shaft-jack placed at the rear of the said bar, substantially as described.

2. A sleigh having a shaft-jack, F, placed at the rear of the front post, substantially as and for the purposes set forth.

3. In a sleigh, a shaft-jack, F, combined with the bar B and the rods G, H, and I, whereby said jack is firmly held in position, substantially as described.

4. In a sleigh, a front arched bar, B, strengthened by the metal strip C, thickest at the bends, and the bent metal strip E at its rear and top, and combined with the runners D, substantially as described.

5. In a sleigh, the combination of the front arched bar, B, strengthened by the metal strip C at its sides and bends, and the bent metal piece E, with the shaft-jack F, rods G, H, and I, and the runners D, substantially as described.

6. In a sleigh, the combination of the arched bar B with the inside curved metal strips, C, one on each side, both thickest at the bends, and each extending from near the middle of the bar to its foot, substantially as and for the purposes set forth.

In testimony whereof I affix my signature in presence of two witnesses.

CHARLES F. KIMBALL.
